CONTAINER

Charles W. Dann, Jr., Miami, Fla.

Application April 20, 1935, Serial No. 17,511

5 Claims. (Cl. 206—44)

This invention relates to containers and has as its object the provision of a container which may be economically produced and which will effectively display the contents thereof; and further to provide such a container adapted for the packaging of any dry foods or beverage products, seeds, materials for domestic pets, etc. and as will be appreciated from a further disclosure of the invention. Further it is an object of the invention to provide a carton or package which will be dust, insect and moisture proof to an effective degree. Further it is an object of the invention to provide such a container or package which when empty may be readily collapsed thereby facilitating and reducing to a minimum the cost of shipping the same to users thereof.

The invention together with its objects and advantages will be best understood from a study of the following description taken in connection with the accompanying drawing wherein:

Figure 1 is a perspective view of the package or container showing the same completely sealed with the contents therein.

Figure 2 is a top plan view of the container or package on a reduced scale.

Figure 3 is a bottom plan view of the container or package on a reduced scale.

Figures 4 and 5 are sectional views taken substantially on the lines 4—4 and 5—5 respectively of Figure 1.

Figure 6 is an elevational view of the container in a collapsed condition.

Figure 7 is a perspective view of the frame in flattened condition.

Referring to the drawing by reference numerals it will be seen that the container or package comprises a frame indicated generally by the reference numeral 10 and which is preferably cut into oblong form from a single blank of cardboard or other suitable material the frame 10 comprising a bottom, top, and side members, the bottom member consisting of flaps 11 adapted to overlap when the frame is worked into shape, and formed by creasing the frame strip on transverse lines 12 spaced inwardly from the opposite ends of the frame strip a distance required by the desired width of the frame.

The top of the frame is indicated by the reference numeral 13 and is formed by creasing the frame strip on spaced transverse lines 14 disposed an equidistance from the transverse center of the strip 10 as best shown in Figure 2.

From the above it will be apparent that the sides 15 and 16 of the frame are constituted by those portions of the strip 10 lying between the

lines 12 and 14 at opposite sides of the transverse center of the strip. The side 15 of the frame which may be constituted as the front side of the frame is preferably provided with a suitable sight opening 15' through which the contents of the package may be viewed.

Further, and in accordance with the present invention a closure flap for the top of the package may be provided by defining on the top member 13 of the frame an area bounded on three sides by lines of perforations 17 and on a fourth side by a fold line 18, the area bounded by these lines 17 and 18 constituting the flap 19.

The top, bottom, and two side walls of the package being formed by the frame in the manner just described the remaining opposed side walls, indicated by the reference numeral 20 are formed from a sheet or wrapping of "cellophane", a cellulose material now known in the trade by such a name, or any other cellulose or transparent material. The sheet is of suitable shape and dimensions so as to provide the aforementioned transparent walls 20 and also to cover completely the outer surfaces of the bottom and side walls of the frame, the "cellophane" being preferably constructed somewhat in the form of a bag to receive the frame 10 with the free edges 21 of the transparent sheet or bag and defining the open top or mouth of the bag, permanently united with the top wall 13 in any suitable manner, preferably by being adhesively secured thereto as to border the top 13 leaving the closure flap 19 easily accessible.

Prior to the filling or placing of the contents into the package the same may be shipped in a folded state as suggested in Figure 6 wherein it will be noted that the transparent envelope is adapted to accommodate the frame strip 10 with the sides of the transparent envelope forming the transparent walls 20 of the package bellowing inwardly and the flaps 11 forming, when the package is completely sealed, the bottom of the package, extended somewhat longitudinally of or in the plane of the sides 15 and 16 of the frame.

Obviously with the parts assembled as suggested in Figure 6 the container may be expanded and filled with the desired contents, assuming, as it is being filled, its final state which is substantially the shape clear from a consideration of Figures 1 to 5 inclusive. In this connection it will be therefore understood that the package is being filled while in substantially an upside down position. When the filling operation has been completed the edge portions of the walls of the transparent envelope are then folded relative to one

another and over the bottom forming, overlapping flap 11 of the frame and secured in this folded condition indicated generally by the reference numeral 22 and clearly shown in Figure 3 which is a bottom plan view of the package when completely filled and sealed. Thus filled and sealed the package is then placed right side up so that indicia such as indicated at 23 printed or otherwise formed on, for example the wall 15 5 may be properly read. Manifestly, with such a package the contents thereof may be readily viewed through the transparent windows 20 and 15'.

After the package has been thus sealed access 15 to the contents of the package may be had by tearing along the lines of perforations 17 and then folding back the flap 19 along the fold line 18, see Figure 5.

It will thus be seen that I have devised a neat 20 attractive package or container whose contents will be effectively displayed, and which package or container will be substantially completely dust, insect and moisture proof so that the package or container may be used for packaging any of the 25 articles and the like hereinbefore enumerated or in addition thereto, novelties such as sea shells, dry paints, pigments, soaps, chemicals and the like.

Preferably, the final shape of the package is 30 as shown, substantially rectangular, so that when filled the same can be packed in carton lots without waste space.

Having thus described the invention, what is claimed as new is:

35 1. A container of the character described comprising an envelope of flexible transparent material and a substantially endless frame of relatively stiff material having only two integral side and end walls respectively arranged within the 40 envelope, said envelope at the end thereof being united with the ends of said frame to provide with the frame a sealed container certain walls of which are transparent and other walls of which are opaque, and said frame having an end 45 portion uncovered and also having delineated on said uncovered portion by weakened lines of severance and a fold line an area defining a closure flap.

2. A merchantable package comprising a container having a pair of opposed side walls and top and bottom end walls respectively connecting said side walls, one of said end walls having a weakened intermediate area providing a normally substantially sealed closure flap for the package, and a transparent wrapper completely surrounding the container with the wrapper at one end having end portions folded inwardly against the second end wall of the container, and said

5 wrapper at its relatively opposite end having portions thereof folded inwardly and adhesively united with the first named end wall of the container with the said united end edges of the wrapper bordering the aforementioned weakened area whereby the latter is completely exposed for accessibility without damage to the transparent wrapper.

3. A container comprising a carton-like frame formed from a blank bent to provide bottom, top 10 and a pair of opposed side walls, the top wall having an integral closure flap connected with the top wall along one edge by a crease line, and at three additional edges by weakened lines of perforations, and a transparent envelope within 15 which said frame is arranged, said envelope being united at its respective opposite ends with the top and end walls respectively of said carton like frame, with the envelope at one end having edge portions bordering said integral closure flap. 20

4. A merchantable package comprising a container having a pair of opposed side walls, and top and bottom walls respectively connecting said side walls, one of said side walls being provided with a sight window, and said top wall 25 having an integral closure flap connected therewith along one edge by a crease line, and at three additional edges by weakened lines of perforations, and a transparent envelope within 30 which said container is arranged, said envelope at one end having edge portions adhesively united with the top wall and bordering said integral closure flap.

5. A collapsible container comprising a carton-like frame formed from a blank of suitable material bent to provide a top wall and two opposed side walls, and transparent material affixed to the carton-like frame forming substantially an integral part thereof; the ends of the said opposed side walls being foldable inwardly one over 40 the other to form a bottom, and said top wall having a weakened intermediate area providing a normally substantially sealed closure flap; said transparent material cooperating with said carton-like frame to form additional opposed confining side walls, and said transparent material also having end edges bent into folded relationship to said top wall and positively united therewith in a manner bordering said closure flap; the transparent material extending unaffixed 45 along the said two opposed walls of said frame, the length of said transparent material being such as to allow the expediency of folding and sealing over the ends of the carton-like frame after said ends have been folded one over the other to form a bottom, whereby to provide a substantially sealed container. 50 55
